AIR HEATER

Edwin Hurford and Richard Johnson,
Detroit, Mich.

Application July 7, 1936, Serial No. 89,396

1 Claim. (Cl. 257—243)

The invention relates to a heater and more especially to an air heater accessory for motor vehicles.

The primary object of the invention is the provision of a heater of this character, wherein the gases from the exhaust of a motor vehicle will be utilized for heating air and such gases in their travel will have a spinning motion within the heater so that quick and thorough heating of air can take place prior to distribution within a vehicle body for heating purposes.

Another object of the invention is the provision of a heater of this character, wherein the same is susceptible of mounting within the exhaust pipe leading from the exhaust side of a motor installed within a motor driven vehicle so that the exhaust can be utilized for the heating of air to be delivered interiorly of the body of the vehicle, the heater being of novel construction.

A further object of the invention is the provision of a heater of this character, which is simple in construction, thoroughly reliable and efficient in its operation, enabling the use of the exhaust gases from an internal combustion engine for the heating of air to be distributed, and inexpensive to manufacture and install.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

In the accompanying drawing:

Figure 1 is a vertical longitudinal sectional view through a heater constructed in accordance with the invention.

Figure 2 is a sectional view on the line 2—2 of Figure 1.

Figure 3 is a sectional view on the line 3—3 of Figure 1.

Similar reference characters indicate corresponding parts throughout the several views in the drawing.

Referring to the drawing in detail, the heater comprises an outer cylindrical body 10 made from sheet metal and has built interiorly thereof a tubular lining 11 separated from the body 10 throughout the longitudinal extent thereof. This lining has the inset annular end portions 12 so that these portions are removed from the ends 13 of the body 10, these end portions being joined with the ends 13 by flange formations 14. The formations snugly embrace a heating drum 15

which is carried centrally through the body and which outside of the body has the contracted portions 16 with pipe extensions 17 which are suitably joined with an exhaust and a muffler as built within a motor driven vehicle. The exhaust gases are admitted from the exhaust of the vehicle motor into the drum 15 through one end thereof and discharged from its other end in the direction of the muffler (not shown).

The lining 11 of the body 10 is set outwardly from the drum 15 to effect an air space 18 concentrically about said drum. Cold air is admitted to the space 18 through an air inlet 19 and discharged from said space after the heating thereof through an air outlet 20, these communicating with the space at opposite ends with respect to the body 10.

Arranged at the longitudinal axis interiorly of the drum 15 is a tubular shell 21 having an outwardly tapered pointed tip or end 22 confronting the exhaust and formed with this tip are spiral vanes or wings 23 so that the exhaust gases entering the drum 15 will effect a spinning motion between the shell 21 and the drum 15 to be carried about the latter in a spiral manner and in this way uniformly heating the air circulating through the space 18 when admitted through the inlet 19 and delivered through the outlet 20. The other end of the shell 21 remote from the tip or end 22 has connection with webs 24 which function to hold the shell centered within the drum 15 while the vanes or wings 23 also center the said shell. The exhaust when spinning about the shell 21 will flow to the muffler for exhaust to the atmosphere.

Within the shell 21 is a filling of a silencing compound 25 for the purpose of silencing the exhaust when passing through the heater, the compound being preferably asbestos and refractor materials.

The construction of the heater as hereinbefore set forth renders the vehicle motor noiseless and eliminates exhaust noises and additionally assures the heating of the air flowing through the space 18 as admitted through the inlet 19 and delivered through the outlet 20.

The body 10 and the lining 11 as constructed affords a dead air space 26 therebetween so that the air circulating through the space 18 is protected against weather elements during the working of the heater.

What is claimed is:

A heater of the kind described comprising a cylindrical body having an internal lining spaced therefrom and forming a dead air space there-

between, a drum fitted centrally within the body and having the lining concentrically spaced therefrom to form an air circulating course, a tubular shell having an outwardly tapered pointed tip and disposed within said drum and spaced from the inner surface of the drum, an air inlet pipe having tangential connection with said air course at one end thereof, whereby air entering the course through the inlet pipe will pass through the course in one spiral direction, means for con-

necting said shell to an exhaust of an internal combustion engine at the end adjacent the air inlet pipe, vanes secured to said tip for imparting to the exhaust a spiral movement opposite to that of the air in the air course, and outlet means for the air and the exhaust at the other end of the shell and air course. 5
